UNITED STATES PATENT OFFICE.

HERBERT ALEXANDER THOMPSON, OF MORPETH, ENGLAND, ASSIGNOR OF ONE-HALF
TO SWINNEY BROTHERS LIMITED, OF MORPETH, ENGLAND, A COMPANY OR-
GANIZED AND EXISTING UNDER THE LAWS OF GREAT BRITAIN.

COOKING STOVE AND RANGE.

Application filed May 12, 1924. Serial No. 712,758.

To all whom it may concern:

Be it known that I, HERBERT ALEXANDER THOMPSON, engineer, a subject of the King of Great Britain, of Wansbeck Ironworks, Morpeth, in the county of Northumberland, England, have invented a new and useful Improvement in or Relating to Cooking Stoves and Ranges, of which the following is a specification.

10 This invention relates to cooking stoves and ranges, particularly ships' galley ranges, and the invention has for its object to provide an improved construction and arrangement thereof.

15 The usual type of galley range is fitted with one or more fires with one or more ovens below the level of what is called the hot plate. We find that with this type of ranges there are serious disadvantages as the 20 flue gases have to be carried over the tops of the ovens and down the sides and underneath the bottom of the same and thence up the back to the chimney.

It is found that with this manner of flue arrangement there is very unequal heating in the ovens with the result that the oven side next the fire invariably burns through and also owing to the intensity of the fire which has to be kept going on account of the poor 30 heating effect contained in the oven, serious burning and damage is caused to the ring plates for the pots which are arranged on the surface of the hot plate.

According to the present invention the 35 oven or ovens and the flues thereof together with by-pass flues are arranged or mounted above or upon the top of the hot plate, so that the flame and gases may come into contact first with the bottom of the oven and 40 then ascend around the oven to the chimney or flue. The fire plate or grate is further so constructed and fitted with demountable parts that the range may be readily converted for firing with either coal or liquid 45 fuel, as may be desired.

The improved range is preferably constructed in the form of right and left hand units or sections, each complete in itself and consisting of one fire box, one oven and end

supporting legs together with the necessary 50 hot plates, flue, and bridge brackets between the fire boxes and the said end legs.

The accompanying drawings show one construction carried out in accordance with the present invention.

Fig. 1 is a front elevation half in section,

Fig. 2 is a part sectional plan,

Fig. 3 is an end elevation partly in section,

Fig. 4 is a sectional end elevation on line X X of Fig. 1.

Fig. 5 is a separate sectional elevation through the grate shown as converted for oil firing.

Fig. 6 is a sectional front elevation of Fig. 5.

Figs. 7 and 8 are respectively inverted plan, and plan of the filling in plate shown in Fig. 5.

Figs. 9, 10, and 11 are respectively front and side elevations and plan of the baffle plate for the bottom of the oven.

The illustrated construction shows a galley range built up of right and left handed sections or units each complete in itself and consisting of one fire box *a* one oven *b*, and 75 end supporting legs *c*, together with the necessary hot plates *d* and bridge brackets *e* carrying the horizontal flues *e* which extend beneath that portion of the hot plate *d* which comes beneath the oven *b*, and between the so fire box *a* and the said legs *c*.

With this arrangement various methods of assembling are possible, for example, the ranges can be built up with the ovens *b* together and the hot plates *d* outside, as 85 shown, or alternatively, the range may be built up with the hot plates together and the ovens at the ends.

In other possible combinations the ranges can be arranged as shown with the two ovens 90 together in the centre and by placing another similar pair back to back with the first set, a surrounding hot plate would thus be obtained with four ovens in the middle.

Various other combinations of the units 95 or sections can be arranged which allows of great flexibility when installing a number of the stoves, as they can be set round a

building in any suitable form of grouping or if one is first installed additional stoves may be added as required.

The parts of the stoves or range will be 5 made interchangeable as far as possible, so that the components will be suitable for right or left hand units.

It will be seen that the ovens *b* are arranged on top of the hot plate, or rather on 10 top of the horizontal flue *e*, which is extended laterally immediately below the level of the hot plate *d* so that an ascending flow of the gases is obtained from the fire boxes *a* beneath the hot plates *d* and into the horizontal flues *e* beneath the oven *b* whilst the 15 gases continue to ascend up the side flues *f* of the oven *b* and over the top by the flue *f'*, and from thence to the chimney *g*.

By using the heat in this manner a much 20 smaller fire can be carried in the fire box, as the whole of the heat is employed in a correct manner by these ascending gases.

The hot plates *d* are fitted in the usual 25 manner with ring plates and apertures for pots.

A single controlling damper *h* is provided under each oven at the outlet opening *h*² from the horizontal flue *e*. The said damper *h* being so arranged that the gases may be 30 directed up the flue *f*² at the back of the oven direct, which will put the oven out of operation, or by reversing the damper by means of its operating rod *h'* the gases will traverse the flues *e*, side flues *f*, and top flue *f'* 35 of the oven. Suitable baffle plates *i* are arranged on the top of the oven in the flue *f'* to direct the gases towards the front of same before travelling back along the top towards the outlet to the chimney *g*.

The fire box *a* is shown in Figs. 1, 2, and 40 3 as arranged for coal burning, being fitted with fire bars *j*, the said fire bars, fire door *k* and bridges being so made as to be easily removable, the arrangement shown is, however, such that all the coal burning fittings 45 except the fire bars *j* and fire door *k* can be left in position if desired when the fire box is converted for oil firing, in which case, as shown in Figs. 5 and 6, there is substituted 50 for the coal burning fire bars a filling in plate *l* which fits into the space left vacant by the removal of the fire bars, the said filling in plate being angled or inclined upwardly at its rear end and provided with serrations 55 or slots *m*. By this arrangement air can be admitted through the ashpit and by passing under the said plate *l* keeps the same cool, and at the same time the air is heated and on passing through the serrations or slots *m* at 60 the end of the plate *l* meets the flame at this point and thus provides a secondary supply of hot air tending to increase the efficiency of combustion.

The filling in plate *l* may be provided, as 65 shown, with suitable ribs *n* at its upper side

to act as stiffeners and also to form retaining ribs for holding fire clay or other refractory material with which these filling in plates *l* should be covered to the level of the top of the ribs to prevent burning of the said 70 plate.

For oil burning a door *o* provided with a suitable oil burner is fitted in place of the coal burning door *k* of Figs. 1, 2 and 3.

It will be seen that with the arrangements 75 described the fire boxes *a* of the ranges can be converted from coal burning to oil burning, or vice versa, in a few minutes so that in cases where both fuels are likely to be used at different times the improved construction provides an effective means for carrying this out.

The improved construction of range has the further advantage that it can be converted to another form of range which is 85 usually termed a native hot plate, i. e. a cooking range without ovens as used where cooking is done for Asiatic crews of steamships. To effect this change all that is required is to remove or omit the ovens from 90 the top of the hot plate *d* and fix a chimney direct to the aperture *h*², which is arranged towards the back of the hot plate and forms the inlet to the oven flues where the latter are 95 fitted.

What I claim as my invention and desire to secure by Letters Patent is:—

1. A stove unit for use in required numbers in ships' galleys comprising a stove structure having a fire box at one end thereof, a hot plate extending over the entire stove structure including the end in which the fire box is situated, a lateral flue immediately beneath the hot plate communicating with the space above the fire box, said hot plate above said flue having an opening at the rear portion of the stove structure, an oven structure fitted directly on the portion of the hot plate above said flue and having bottom, side and top flues about the oven with the rear portion of the bottom flue communicating directly with the opening in said hot plate, a chimney communicating with the top flue of the oven structure, baffle plates in said flues of the oven structure, and a damper extending in common to the bottom flue of the oven structure and said opening of the hot plate and adapted to direct the products of combustion either to said bottom flue or to the chimney. 105 110 115 120

2. A stove unit for use in ships' galleys comprising a stove structure having a fire box at one end thereof, a hot plate extending entirely over the stove structure and above the fire box, a supporting leg at the opposite end of the stove for sustaining the hot plate, a horizontal flue communicating with the space above said fire box and arranged between said fire box and said supporting leg, said horizontal flue being 125 130

directly beneath said hot plate, said hot plate having an opening at the rear portion of said flue, an oven structure placed directly upon said hot plate and having a bottom flue whose bottom wall is said hot plate, said oven structure also having side, top and a back flue, said back flue and bottom flue communicating with the opening in said hot plate, a damper pivotally mounted in said

oven structure and having its free end 10 adapted to engage either forward or rear edge of said hot plate opening to direct the products of combustion either to the bottom, side and top flues or directly to said back flue, and a chimney communicating with 15 said back and top flues.

HERBERT ALEXANDER THOMPSON.
